(57) **CLAIM**

The ornamental design for a box for office supplies, as shown and described.

DESCRIPTION

FIG. 1 is a top, front and side perspective view of a box for office supplies, showing my new design;

FIG. 2 is a top, rear and side perspective view thereof;

FIG. 3 is a view similar to FIG. 1, the lid being in a partially opened position;

FIG. 4 is a side elevational view thereof, the side elevational view opposite that shown in FIG. 4 being the mirror image thereof;

FIG. 5 is a front elevational view;

FIG. 6 is a rear elevational view thereof;

FIG. 7 is a top plan view thereof; and,

FIG. 8 is a bottom plan view.
